UNITED STATES PATENT OFFICE.

WILLIAM KAUTZMAN, OF NEWARK, NEW JERSEY.

DESIGN FOR A FLAG OR EMBLEM.

56,882.

Specification for Design.

Patented Jan. 4, 1921.

Application filed April 8, 1920. Serial No. 372,366. Term of patent 3½ years.

To all whom it may concern:

Be it known that I, WILLIAM KAUTZMAN, a citizen of the United States, residing at Newark, in the county of Essex and State of New Jersey, have invented a new, original, and ornamental Design for a Flag or Emblem, of which the following is a specification, reference being had to the accompanying drawing, forming part thereof.

The figure is a plan view of a flag or emblem showing my new, original and ornamental design.

I claim:

The ornamental design for a flag or emblem as shown.

WILLIAM KAUTZMAN.
